(74) Attorney, Agent, or Firm — Andrew F. Young, Esq.;
Lackenbach Siegel, LLP(57) **CLAIM**

The ornamental design for a jewel design, as shown and described.

DESCRIPTION

FIG. 1 is a front perspective view of the present invention.

FIG. 2 is a top plan view of FIG. 1.

FIG. 3 is a front elevation view of FIG. 1, the rear elevation view being a mirror image thereof for symmetry.

FIG. 4 is a left side elevation view of FIG. 1, the right side elevation view being a mirror image thereof for symmetry; and,

FIG. 5 is a bottom plan view of FIG. 1.

The surfaces are lightly lined for contour only.
